UNITED STATES PATENT OFFICE.

ALVIN V. ROWE, OF GALESBURG, ILLINOIS.

GATE-HINGE.

1,316,062.

Specification of Letters Patent. Patented Sept. 16, 1919.

Application filed May 3, 1918. Serial No. 232,234.

To all whom it may concern:

Be it known that I, ALVIN V. ROWE, a citizen of the United States, and a resident of Galesburg, in the county of Knox and State of Illinois, have invented a new and useful Gate-Hinge, of which the following is a specification.

The present invention relates to lower hinges for tilttable and elevatable farm gates, to operate harmoniously with the general class or character of upper hinges shown in the accompanying drawings but which is much more fully described and illustrated in my co-pending application Serial No. 221,171, filed March 18, 1918.

In this type of gates it becomes necessary to space the upper gate-board quite a little distance from the supporting post, the next lower post a little less distant and so on down to the lowermost board. Heretofore, within my knowledge, no hinge has been devised which will bring the lowermost board very close—in fact, almost in contact with the post, and the result has been that pigs, hogs, sheep and other small animals crawl between the post and the adjacent ends of the gate-boards and into the wrong enclosure.

One of the principal objects of the invention is to provide a hinge possessing such structural features as will permit the inner end of the lowermost gate-board to be brought very close to the supporting-post and, consequently, the inner end of the other boards to be brought correspondingly closer to the post.

Another object is to provide a lower hinge which will operate successfully in connection with most, if not all of the class of upper hinges hereinabove referred to.

Another object is to utilize the inner standard as the lower pintle, thus bringing the lower end thereof very close to the supporting post.

Still another object is to provide a novel adjusting element which functions also as a hinge-member.

Other objects will presently appear. Some of these will be obvious and some pointed out.

The invention consists, substantially, in the improvements herein disclosed.

In the accompanying drawing, which illustrates a preferred embodiment of my invention:

Figure 1 is a side elevation of a gate embodying my improvements and in what may be termed its normal position;

Fig. 2, a side elevation showing the gate in tilted position;

Fig. 3, a very slightly modified form,—the modification, however, being in the lower gate-board and not in the hinge—shown in elevated position;

Fig. 4, an enlarged transverse section, 65 taken in the plane of the line 4—4 in Fig. 3; and

Fig. 5 an enlarged detail in side elevation.

Referring to the drawings by numerals, 70 2 designates a supporting-post to which is secured a gate-hook 3 which is engaged by the hinge-rod 4 of the upper hinge disclosed in my co-pending application above referred to.

5, 6, 7, 8 and 9 designate the boards of a gate in which the usual vertically arranged standards 10 and bolts and nuts 11 or other securing means are employed to unite them. 80 12, 12 designate braces, and 13, 13 indicate the inclined pair of standards at the inner end of the gate.

14 denotes an eye-bolt the shank of which is suitably secured to the post.

15 indicates an adjusting and locking 85 sleeve. Preferably it is a stamping or die-formed piece the opposite sides of which constitute channels 16 in which the standards 13 respectively seat. Its rear portion or back comprises a pair of parallel jaws 17 united 90 by a curved back-proper 18. At the upper portion of its longitudinally slotted front 19 is a pair of apertured tongues 20 which lie on opposite sides of the board 8 and secured

- thereto by bolts 21 and nuts 22. Each of the sides is provided with a series of cotter-pin holes 23. The back is cutaway at 24 and 25 and the front at 26 and 27 sufficiently for the passages of the boards. In Fig. 5 the board 8 will be seen as resting on the shoulders 24 and 26 afforded by said cutaway portions, and in Fig. 1 the board 9 is resting on the shoulders 25 and 27. 28 designate 5 rearwardly projecting lips one at the lower terminal of each cheek 17. When the lower ends of the standards 13 are united by means of the bolt or other securing means 31 and the coacting nut (not shown) drawn 10 taut, the lips 28 will be forced tightly against and their tips forced somewhat into the wooden board 9 to thereby provide additional means for holding the sleeve 15 in 15 position.
- 20 29 designates a ring or washer and 30 a cotter pin.

In Fig. 1 the gate is shown in its normally closed and lowermost position. In order to position it as shown in Fig. 2 all 25 that is required is to lift it to that position and then free it, for any of the many upper-hinges adapted for this purpose will operate, and the element 15 will slide upwardly through the eye of the bolt 14 and the opening 30 in the washer 29. The web of the latter is preferably quite wide, in order, first, that it may turn freely on top of the bolt 14, and secondly, that it may furnish a firm support for the cotter. Attention is called at this 35 time to the fact that in general cross-section the sleeve 15 is circular in order, primarily, that it may turn freely in the eye-bolt and washer.

In order to position the gate as shown in 40 Fig. 3 it is necessary to cut away a small corner-piece from the board 9, as shown best at 34, Fig. 5. When the operator has raised the gate to the desired position—the element 15 sliding, as above described, 45 through the eye-bolt and washer—he will insert the cotter-pin or any other suitable means through one of the holes 23, or through registering ones thereof. The cotter will rest on the upper face of the washer 50 and the weight of the gate will come upon the eye-bolt 14.

In any of the positions shown in the drawings the gate will swing with the greatest of freedom. I wish, in this connection, to 55 call particular attention to the fact that the standards 13 constitute the lower pintle, and that the element 15 is a sleeve whereby the gate may be locked in selective elevated position by means of the apertures 23 and cotter 30.

Having thus described my invention I claim as new the following, to-wit:

1. In a gate of the type described, a sup-

porting-post, a gate-body comprising gate-boards and a pair of inclined standards 65 uniting them, means for hinging the inner upper portion of the gate-body to the post, an eye-bolt, constituting a lower hinge-member, secured to the lower part of the post, and an adjusting-element embracing said inclined standards and passing through the eye of the eye-bolt.

2. In a gate of the type described, a supporting-post, a gate-body comprising gate-boards and a pair of inclined standards 75 uniting them, means for hinging the inner upper portion of the gate-body to the post, an eye-bolt, constituting a lower hinge-member, secured to the lower part of the post, an adjusting-element embracing said 80 inclined standards and passing through the eye of the eye-bolt, and means for locking the adjusting element in selective position relative to the eye-bolt.

3. In gates of the character described, a 85 supporting-post, a gate-body including gate-boards and a pair of inclined standards uniting them, means for hinging the upper portion of the gate-body to the post, an adjusting-sleeve embracing said standards and 90 secured to one of the gate-boards, said sleeve provided near its upper portion with shoulders on which one of the gate-boards may rest and near its lower portion with shoulders adapted to rest upon another gate-board, and a ring-like lower hinge-member 95 secured to the post and coöperating with the sleeve.

4. In gates of the nature described, a supporting-post, a gate-body including gate-boards and a pair of standards uniting them, means for hinging the upper portion of the gate-body to the post, an adjusting-sleeve embracing said standards and secured 100 to the gate-body, and a ring-like lower 105 hinge-member secured to the post and in which the sleeve is adapted to rotate.

5. In gates of the nature described, a supporting-post, a gate-body including gate-boards and a pair of standards uniting them, means for hinging the upper portion 110 of the gate-body to the post, an adjusting-sleeve embracing said standards and secured to the gate-body, a ring-like lower hinge-member secured to the post and in which 115 the sleeve is adapted to rotate, and means for locking the adjusting sleeve in selective elevated positions relative to the ring-like member.

6. In gates of the nature described, a 120 supporting-post, a gate-body including gate-boards and a pair of standards uniting their inner ends, means for hinging the upper portion of the gate-body to the post, an adjusting sleeve embracing said standards and 125 secured to the gate-body, said sleeve pro-

vided at its rear side with a cutaway portion in which one of the gate-boards seats, and having a projecting tongue adapted to be pressed tightly against one of the gate-
5 boards, means for causing one of said stand-
ards to press said tongue against said board,
a ring-like lower hinge-member secured to

the post and in which the sleeve may ro-
tate, and means for locking the sleeve in
vertically adjusted position relative to the 10
ring-like hinge-member.

In witness whereof I hereunto sign my
name this 27th day of April 1918.

ALVIN V. ROWE.
